CLAIM

The ornamental design for a vehicle tailgate protective pad, as shown and described.

DESCRIPTION

FIG. 1 is a front and top perspective view of a vehicle tailgate protective pad, showing my new design;

FIG. 2 is a rear and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing the vehicle tailgate protective pad in an unfolded position; and,

FIG. 10 is a perspective view thereof, showing keys removed from the vehicle tailgate protective pad.
